US00D931760S

(12) **United States Design Patent** (10) **Patent No.:** **US D931,760 S**
(45) **Date of Patent:** **** Sep. 28, 2021**

(54) **ELECTRIC BIKE**

(71) Applicant: **ENERMAX TECHNOLOGY CORPORATION**, Taoyuan (TW)

(72) Inventor: **Yen-Wen Su**, Taoyuan (TW)

(73) Assignee: **ENERMAX TECHNOLOGY CORPORATION**, Taoyuan (TW)

(**) Term: **15 Years**

(21) Appl. No.: **29/749,869**

(22) Filed: **Sep. 9, 2020**

(51) LOC (13) Cl. **12-11**

(52) U.S. Cl.

USPC **D12/111**

(58) **Field of Classification Search**

USPC D12/110, 111, 117; D21/432, 538

CPC B62K 11/00; B62K 11/02; B62K 11/04;
